UNITED STATES PATENT OFFICE.

HENRY HUMPHREVILLE, OF MOUNTVILLE, PENNSYLVANIA.

AIR-PUMP.

SPECIFICATION forming part of Letters Patent No. 251,886, dated January 3, 1882.

Application filed October 25, 1881. (No model.)

To all whom it may concern:

Be it known that I, HENRY HUMPHREVILLE, a citizen of the United States, residing at Mountville, in the county of Lancaster and State of Pennsylvania, have invented certain new and useful Improvements in Air-Pumps; and I do hereby declare the following to be a full, clear, and exact description of the invention, such as will enable others skilled in the art to which it appertains to make and use the same.

The object of my present invention is the improvement of the form of air-pumps for atomizers, Letters Patent for which were granted to me July 26, 1881, No. 244,901, which was designed to provide suitable means for forcing a current of air through an atomizer of the form also patented to me March 2, 1880.

My improvement consists in dispensing with certain features of my patent of July 26, 1881, such as an outer air passage or chamber annexed to and leading from the front to the rear of the cylinder and communicating with said cylinder by means of certain apertures, also with certain valves, diaphragm, outer apertures, stuffing-box, &c., constituting a double force-pump, and in constructing as a substitute therefor a single force-pump more simple in construction and efficient in operation. I also show my present improvement attached to my spring-dampener of March 2, 1880; but it will be perfectly obvious that it may be applied to many other forms of atomizers.

My improvement is illustrated in the accompanying drawings, in which Figure 1 represents an exterior view of the same with the spray-dampener attached thereto, and Fig. 2 a longitudinal sectional view of my device.

A indicates a cylinder, constructed of metal or other suitable material, with a convex bottom, b, and provided with a nozzle, C, over which is drawn a rubber cover, o, to serve as a tight packing for the tube of the atomizer when the latter is attached thereto. The bottom b is made convex to give it greater strength and afford a stronger and more durable support to the nozzle C. Its inner concave surface also constitutes a sort of cup for holding oil by which the parts are lubricated.

The inner end of said nozzle is extended through

said bottom and into the body of the cylinder for a short distance, as shown, in order that the oil used as and for the purpose just mentioned may not be blown into and through the atomizer, and thus mingle with or injure the contents of the atomizer and obstruct its operation.

D indicates the piston-rod, and E the air-tight piston, the latter being constructed of a disk of rubber or leather, f, held between two metal plates, g and h, by means of nuts l and l', and with its edges turned down over the lower plate. The lower metal plate, h, is made slightly concave on its under side in order that its edges may not cut the disk, and to give to the piston a close and neat fit to the walls of the cylinder.

It will be seen that the face of the lower nut, l', is made perfectly flat, so that when the piston is forced down its entire length the face of the nut will fit closely upon the inner mouth of the nozzle C.

L is a cap, which is screwed onto the cylinder. Through this cap the piston-rod is moved, and the cap is made of the elongated form shown for the express purpose of better supporting the piston-rod in a horizontal position when the rod is drawn back its entire length. Cap L is also provided with one or more apertures, m, for the admission of air into the cylinder behind the piston and for its egress when the piston is raised.

In operation air is drawn through the atomizer directly into the cylinder by way of nozzle C, and in forcing the air-tight piston E quickly down upon the nozzle C, a strong current of air is forced into the atomizer, the contents of which are forced out as efficiently as with a double force-pump, and at the same time the use of diaphragms, valves, outer apertures, chambers, and stuffing-box are dispensed with, which greatly lessens the cost of production and the liability to get out of order.

An additional plate or diaphragm, if desired, may be set in the elongated cap L at i, through which the piston-rod may be passed as an additional support and to make a closer joint; but in practice it is thought the use of this plate will be unnecessary.

Having thus described my invention, what I

claim, and desire to secure by Letters Patent, is—

1. An air-pump provided with a convexo-concave bottom, in combination with a nozzle which extends into the pump-cylinder for a sufficient distance, as and for the purpose described.

2. The combination, in an air-pump designed to be used with atomizers, of cylinder A, elong-

gated screw-cap L, bottom b, piston E, and nozzle C, extending into the pump-cylinder, substantially as described.

In testimony whereof I affix my signature in presence of two witnesses.

HENRY HUMPHREVILLE.
